UNITED STATES PATENT OFFICE.

FRED FORREST PEASE, OF EAST BRAINTREE, MASSACHUSETTS, ASSIGNOR TO F. F. PEASE INC., OF BOSTON, MASSACHUSETTS, A CORPORATION OF MASSACHUSETTS.

AIR-CLEANING APPARATUS.

Application filed April 5, 1923, Serial No. 630,024. Renewed July 29, 1926.

The present invention relates to air washing or cleaning apparatus and more particularly to apparatus of this character designed for cleansing the air of impurities which cannot ordinarily be removed therefrom by usual methods.

The object of the present invention is to provide a new and improved type of apparatus for removing both coarse and finely divided solids, together with gases which may be present in the air.

With this object in view the various features of the invention consist in certain novel features of construction, combinations and arrangements of parts hereinafter described and claimed, the advantages of which will be obvious to those skilled in the art from the following description.

In the accompanying drawings illustrating the preferred form of the invention Fig. 1 represents an elevation largely in section of an apparatus embodying the features of the invention, and Fig. 2 is a detail illustrating a section of the mechanism for spraying a liquid into the air.

According to the present invention the air to be cleansed is initially impregnated with a spray of cleansing liquid, such as water, which serves to dissolve or precipitate solids and gases from the air. Thereafter the liquid containing the solids or dissolved gases is completely separated from the air by a revolving screen which permits the air to pass freely therethrough while removing the liquid therefrom through contact with the solid portions of the traveling screen surface. The liquid is conveniently caused to intermingle with the air by a rotary atomizing cup from the peripheral edge of which a spray of liquid is delivered. This liquid spray issues from the atomizing cup in a thin sheet and intimately mingles with the body of air, serving to wash out impurities. After treatment with the cleansing liquid, the air passes through a chamber of sufficient length to permit the atomized liquid to thoroughly intermingle therewith and wash out impurities and subsequently encounters the revolving screen separator which removes the liquid from the air in a simple and efficient manner.

Referring to the illustrated embodiment of the invention, the air washing chamber indicated at 10 is provided at one end with an air intake duct 12 of smaller size in which

is located the liquid spray mechanism 14. The opposite end of the air washing chamber is provided with a revolving separator 16 which may be mounted upon the fan shaft 18. The circulation of air through the chamber may be accomplished by an exhaust blower indicated generally at 20 and mounted upon the shaft 18, this blower being driven by a drive pulley 22 actuated in any suitable manner (not shown).

The liquid for cleansing the air which may be hot or cold water or an alkaline or acid solution is intermixed with the air through a rotary atomizing cup 24 having outwardly flaring funnel shaped walls 26 communicating with a feed pipe 28 passing through the interior of the cup. The cup is provided with an extended sleeve portion 30 journaled for rotation in an outer bearing 32, which in turn is supported within the casing 10 through a skeleton support 34. The feed pipe 28 passes through a longitudinal bore formed in the interior of the sleeve 30 and permitting the latter to revolve freely about the pipe. With this construction, liquid passing through the pipe under suitable pressure is delivered to the surface 26 and after passage thereover is discharged centrifugally from the peripheral edge 36 in a conical stream, as indicated generally by dot and dash lines. This construction provides for an intimate intermixture of the liquid and air without the employment of small orifices or similar constructions which are easily clogged and liable to derangement. It will be evident that with this construction a quantity of liquid is sprayed in excess of the amount which the air can absorb or cause to evaporate, the surplus water washing out the impurities and being thereafter separated. The atomizing cup may be conveniently rotated through the use of a series of fan blades 40 extending radially from the outer portion of the cup and located in the path of the air drawn through the comparatively small intake 12. This incoming draft of air is of sufficient force to rotate the cup and nozzle at high speed and provide for the necessary atomizing and spraying of the liquid. If the current of air is not sufficient to rotate the cup at the desired speed under certain conditions of operation, external driving connections may be provided for the purpose of positively rotating the cup.

The air mixed with an excess of liquid

after passage through the washing chamber 10 encounters a revolving screen surface which may be a disk consisting of screen wire of suitable mesh revolving at a rate of speed to cause a substantially complete separation of the liquid and foreign matter but permitting a relatively free passage of air therethrough. To this end, as indicated, a flat screen 16 is mounted at its periphery 15 upon a spider 50 having a hub 52 secured to the fan shaft 18. The spider is provided at its periphery with an annular rim portion 54 to which the edge of the screen is secured. The peripheral portion of the screen travels in an annular recess 56 formed in the casing and serving to collect and discharge the dirty liquid into a pipe 58 communicating with the bottom portion of the recess. As will be evident to those skilled 20 in the art, the liquid impinges upon the solid portion of the screen and is thrown therefrom by centrifugal force into the recess passing downwardly about the annular recess and outwardly through the pipe 58. 25 Not only is the liquid separated from the air through the use of this screen but in addition solid matter which may not have been washed out by the liquid is also engaged and separated from the air through 30 the rotation of the screen. The mesh of the screen and its speed of rotation are designed to accomplish a substantially complete separation of all liquid which has not been evaporated from the air. If so desired, the central portion of the screen may 35 be blocked off in any suitable manner so that the liquid encounters only the outer portions of the revolving screen. In addi-

tion the screen may be driven independently of the fan and at a different speed. 40

While it is preferred to employ the specific construction and arrangement of parts shown and described it will be understood that this construction and arrangement is not essential except so far as specified in the claims and may be changed or modified without departing from the broader features of the invention. 45

The invention having been described, what is claimed is: 50

1. Air cleaning apparatus comprising an elongated settling chamber, a rotary atomizing cup positioned at one end of the chamber, an air intake surrounding the atomizing cup and adapted to be impregnated with liquid spray from the cup, a rotary screen separator located at the opposite end of the chamber and designed to remove entrained liquid and impurities from the air, and means beyond the screen separator for causing a movement of air and liquid through the chamber. 55

2. Air cleaning apparatus comprising an elongated settling chamber having a reduced intake portion, a rotary atomizing cup journaled for rotation within the intake, means for supplying liquid to the atomizing cup, a rotary screen separator positioned at the opposite end of the chamber and located and designed to cause substantially all of the air to pass therethrough removing liquid and impurities therefrom, and means located beyond the screen separator for causing a flow of air and liquid through the chamber. 60 65 70
